CATAMARAN OFFSHORE DRILLING VESSEL
Charles E. Thornton, Tulsa, Okla., and George L. Temple, Houston, Tex., assignors to Reading & Bates Offshore Drilling Company, Tulsa, Okla., a corporation of Delaware

Filed July 10, 1963, Ser. No. 294,137
9 Claims. (Cl. 114—5)

This application comprises a continuation-in-part of our applications entitled, "Catamaran Type Offshore Drilling Rig," Serial No. 153,592, filed November 20, 1961, and Serial No. 195,440, filed May 17, 1962, now both abandoned.

This invention relates to a catamaran offshore drilling vessel and has as its primary object the provision of an improved offshore drilling rig characterized by a pair of spaced hull means of catamaran type with a drilling platform and rig positioned thereon, the hull means being secured together or integral to insure greater stability of the rig and its associated parts.

An additional important object of the invention is the provision of an offshore drilling rig which by the arrangement of its catamaran type hull means is readily adaptable to comparatively great depths of water as well as high wave conditions, to which conditions currently employed offshore drilling rigs are unable to adapt.

As conducive to a clearer understanding of this invention, it may here be pointed out that several methods of offshore drilling are currently employed. Such methods include the use of drilling tenders tied alongside a drilling platform erected offshore, with the actual rig for drilling the well being located on a stationary platform, the legs of which may extend many feet under the water and be sunk in the bottom. Another method employs the so-called self-elevating barge which is towed to the desired location and which is provided with legs which are then lowered to the floor of the sea, the derrick and rig for drilling the well being subsequently positioned on the barge platform, and the well is drilled. At the conclusion of the drilling of such a well, if a tender is employed the platform is either left in place for production if a producing well is achieved or dismantled if a dry hole results, and the drilling tender is towed to another location. With respect to the barge or self-elevating platform, in the case of a producing well a stationary platform is erected for production, and a self-elevation drilling barge is towed to another location. Both of these methods are limited by the depth of the water, and in many instances, by the wave action at the particular location. Obviously, the erection of a platform, or the use of a self-elevating barge as described is limited by the depth of the water. An important object of the invention is, therefore, the provision of a catamaran type offshore drilling rig which may be towed to the desired location, and suitably anchored, and drilling conducted from the platform between the catamaran hull means regardless of the depth of the water.

Applicants are also aware that some deep water drilling has been achieved by means of barges, wherein the drilling unit and rig are operated through an opening in the center of the barge. Under such conditions the barge may be held in place when the water is too deep for anchors by outboard motors extended over both sides and operating at such speeds and power as may be necessary to hold the barge directly over the drill pipe. An additional important object of the instant invention is the provision of a means providing all of the advantages of the above-described method but providing an increased buoyancy factor and a relatively large deck area which is incompatible with the organization of the barge having the center hole.

2

Applicants are also aware that drilling has been effected from a barge which is not anchored to a platform where-in the rig is extended over one side of the barge and counterweights are provided at the water line on the opposite side of the barge. An important object of the instant invention is to overcome the difficulties of the last-mentioned arrangement by the provision of a catamaran type hull means wherein the increased buoyancy factor is occasioned by the reduction of weight afforded by the omission of the counterweight, as well as the elimination of much non-useable space in which drilling mud, fuel, supplies, etc., may be stored. In both of the last-mentioned types of drilling, the effective deck area is much less than that achieved by the instant invention.

The arrangement of the vessel with its two hull means separated to give a widespread, stable base provides superior behavior in waves during drilling operations, as well as when riding out a storm or under tow. To appreciate the features of the catamaran arrangement, consider first the poor behavior and limited operating capacity if it were a single hull drilling vessel. The conventional single hull means is notoriously sensitive to rolling, particularly in waves that have a frequency close to the natural frequency of roll of the ship. Under this condition, extremely large angles of roll can occur even with the wave approaching nearly head-on or stern-on, and even if the height of the wave is small. Therefore, it would be necessary to lay the vessel head-on or nearly so to the prevailing waves, which then requires that the derrick be located near amidships in order to reduce vertical movements due to pitching. Drilling could then be accomplished through a center well, which position minimizes roll as well as pitch but which limits drilling operations to underwater completions, and presents difficulties in getting on and off a well when the occasion requires. Drilling could also be accomplished from an "over the side" position which makes well completion and positioning easier, but which then subjects the drilling rig to large rolling motions should waves arise from other than the head sea direction. Such is the case with ground swells, which may be long and flat, heading in a different direction, from a storm area several hundred miles away, and which can set up unexpected and severe rolling. All in all, the sensitivity to rolling, the continual disturbance due to pitching which must be abided in order to minimize rolling, the discomfort and inefficiency of the crew under these conditions, and the possible high stresses occasioned in the derrick along with the difficulties of handling drill pipe, make the use of a single hull drilling vessel unattractive and operationally uneconomical.

The catamaran arrangement provides a more stable working platform over a wider range of conditions. Having great righting stability, the vessel will not roll in its own period to large and dangerous angles, even in strong seas. At most, in long beam seas, it will roll to the slope of the waves, which seldom exceed 9-10 degrees even when at storm height. In shorter waves, the tendency of the widespread hull means to straddle the crests or troughs of the waves reduces the roll angles to considerably lower values. The straddling characteristic also tends to reduce the motions and accelerations of heaving (the rise and fall of the ship with the wave). One generally unnoticed but important characteristic of the catamaran is that, due to its tendency to follow the slope of the beam sea, its center of roll motion is well above the water line. Thus, in the vicinity of the drilling floor or slightly above, the roll motions and accelerations should be minimum. The single hull vessel, on the other hand, rolls at a center close to the water line, thus causing appreciable transverse motion and acceleration at any

fair height above the water. The pitching characteristics of the catamaran vessel in head seas are essentially no different from those of the single hull ship. However, due to the moderate roll behavior of the catamaran there is no need to stay head-on to the waves during operation. In fact, it is the feature of being able to operate with a minimum of disturbance over a wide range of approaching wave directions that is probably the single most important characteristic of the catamaran ship. When quartering to the sea, both roll and pitch motions are present but both are at reduced intensity. Therefore, there should be less need to reposition the vessel to suit a change in prevailing sea direction, and less chance of having to suspend operations in a strong, confused sea.

While the twin hull means must be spaced apart to provide the improved stability of the catamaran relationship, it is important that they not be unduly separated since the great weight of the drill pipe and the torque imparted by the rotary drilling table would pull the hull means downwardly and inwardly if an excessive separation were provided. It has been found that to provide excellent stability characteristics while precluding undue strain on the vessel, the separation should be limited to not in excess of the beam dimension of one of the hull means.

The greatly reduced motions under a wider range of sea conditions allows the placement of the derrick in its most desired position—in a slot at the aft centerline of the vessel. This allows for greatest ease in getting on and off, as well as for completing wells above water and setting jackets. Also, in the event of a fire at the well head the vessel may readily be towed or self-propelled forward while fire boats and other equipment is brought in to fight the fire. In contrast, if the fire were amidships, the entire drilling structure and vessel may be destroyed, or at the very best, it would be necessary to break off the drilling connection and perhaps lose the well. This would require excessive salvage costs after the fire was extinguished in moving back over the drill pipe, replacing broken or damaged pipe, the well fixtures and the like. Similarly, during a period of hurricane weather, a vessel having its drilling derrick at its stern, could move quickly away from the drilling operation, whereas in an amidship construction, the well head and the like must be severed causing the expenditure of much time and money. Moreover, a stern mounted drilling derrick facilitates folding or pivoting the same to lower the center of gravity and decrease the height of a vessel during transportation, while not affecting the maneuverability of the same. Further, there is less likelihood of losing a well if a mooring cable should let go forward or to the side, since the vessel would tend to pivot about the well center. All of this means less risk in staying on location longer, both in continuing to work in seas stronger than could be tolerated with a single hull ship and in affording more time to make preparations to move off in the face of a severe storm.

In view of the type of operation for which the structures of the instant invention have been designed, that is, an oil drilling operation, wherein the only buoyancy of the drill pipe is in that portion from the surface of the water to the ocean floor, perhaps two hundred to three hundred feet, with some eleven to thirteen thousand feet of pipe below the ocean floor, a great strain is presented to the vessel requiring extremely rigid and sturdy means connecting the twin hull means in order to avoid damage to the same. The two hull means may be tied together by a series of rugged trusses at both ends of the ship, at the aft end forming part of the derrick substructure and at the forward end, the helicopter platform. Model test results, wherein the forces on the ship were determined for extreme storm conditions, indicate that the catamaran vessel will not be subject to racking or bending stresses that would be any more severe than those experienced

by the same hull means as single, individual vessels under the same conditions.

Alternately, and according to a further embodiment of the instant invention, the catamaran offshore drilling rig 5 may be integrally formed, the two hull means communicating with, and forming part of, the connecting structure, thereby increasing the strength and usable space of the vessel.

The catamaran offshore drilling vessel of this invention 10 may either be self-propelled or towed, the former construction providing increased mobility and flexibility in use.

Another very important object of this invention is the 15 provision of a catamaran type of drilling rig having a pivotally mounted derrick, which may be lowered during transport to permit the passage of the rig beneath bridges, and also to lower the center of gravity of the rig during towing or transport from one location to another when the rig is not in use.

An additional object of the invention is the provision 20 of a rig of this character provided with an open deck area affording space for the landing and take off of helicopters for transport of personnel and supplies as may be necessary.

Additional objects reside in the combinations of elements, arrangements of parts, and features of construction.

Still other objects will in part be obvious and in part 25 be pointed out as the description of the invention proceeds and shown in the accompanying drawings wherein:

FIGURE 1 is a side elevational view of one form of catamaran type offshore drilling rig embodying the instant inventive concept;

FIGURE 2 is a top plan view of the rig of FIGURE 1, 30 certain concealed portions thereof being indicated in dotted lines;

FIGURE 3 is a fragmentary schematic plan view of one form of layout of space in the deck house;

FIGURE 4 is a plan view of the main deck level;

FIGURE 5 is a view similar to FIGURE 4 of the hold;

FIGURE 7 is an enlarged sectional view taken substantially along the line 7—7 of FIGURE 6 as viewed in the direction indicated by the arrows;

FIGURE 8 is an enlarged sectional view taken substantially along the line 8—8 of FIGURE 2 as viewed in the direction indicated by the arrows;

FIGURE 9 is an enlarged sectional view taken substantially along the line 9—9 of FIGURE 2 as viewed in the direction indicated by the arrows;

FIGURE 10 is a front elevational view of the drill rig as shown in FIGURE 1;

FIGURE 11 is a fragmentary side elevational view showing a modified form of drill rig construction and a portion of a modified form of hull means to accommodate such rig;

FIGURE 12 is a fragmentary plan view of a modified 60 form of construction of the stern portion of FIGURE 2 embodying the derrick or drill rig of FIGURE 11;

FIGURE 13 is a fragmentary view of a portion of one hull means similar to FIGURE 4 but showing a modified form of arrangements of components;

FIGURE 14 is a view similar to FIGURE 13 but showing a further modified arrangement of hull components;

FIGURE 15 is a fragmentary diagrammatic plan view showing a modified form of the interior components of one of the hull means at the deck level of FIGURE 4;

FIGURE 16 is a fragmentary plan view showing a modification of one of the hull compartments at the deck level of FIGURE 5;

FIGURE 17 is a similar fragmentary view showing a modified arrangement of hull components at the deck level of FIGURE 5 at the bow of one of the hull means.

FIGURE 18 is a top plan view similar to FIGURE 2 but showing a modified form of construction wherin the drill rig is mounted amidships rather than at the stern of the vessel;

FIGURE 19 is an enlarged sectional view taken substantially along the line 19—19 of FIGURE 18 as viewed in the direction indicated by the arrows;

FIGURE 20 is an enlarged sectional view taken substantially along the line 20—20 of FIGURE 18 as viewed in the direction indicated by the arrows;

FIGURE 21 is an enlarged sectional view taken substantially along the line 21—21 of FIGURE 18 as viewed in the direction indicated by the arrows;

FIGURE 22 is a right or starboard side elevational view of a unitary, self-propelled embodiment of catamaran offshore drilling rig in accordance with the instant inventive concept;

FIGURE 23 is a fragmentary top plan view of the heliport deck of the embodiment of FIGURE 22;

FIGURE 24 is a plan view of the drilling floor and upper deck arrangement;

FIGURE 25 is a plan view of the main deck level;

FIGURE 26 is a view similar to FIG. 25 of the second deck arrangement plan;

FIGURE 27 is a similar view of the third deck level;

FIGURE 28 is a plan view of the tank top and inner bottom arrangement plan; and

FIGURE 29 is a front or bow end elevational view with a portion of the drilling rig broken away for illustrative convenience.

Similar reference characters refer to similar parts throughout the several views of the drawings.

Having reference now to the drawings in detail, particularly FIGS. 1-10, there is generally indicated at 30 a catamaran type of well drill rig which is comprised of a pair of hull means 31 and 32, which, in external configuration, are substantially identical, although their interior components may be varied, as will be described more fully hereinafter. The hull means 31 and 32 are rigidly secured together so that they will act as a stabilizing platform for a drill rig derrick 33 and its associated mechanism.

In the form of the invention disclosed in FIGURES 1 to 10, inclusive, the drill derrick 33 includes a lower reinforced tapered section 34 which comprises a pair of divergent legs, each of which is pivotally mounted as on a pivot 35 secured to a supporting member 36 carried by a drill platform 37. The drill platform 37 supports a drill operating enclosure or deck house 38 which contains the usual winch for operating the drill line 39, which extends through the usual pulleys 40 at the top of the derrick or drill rig 33. Rearwardly extending supporting braces 41 are pivotally secured as at 50 to the upper extremities of legs 34 and releasably secured as at 51 to platform 37, the arrangement being such that upon release of the connections 51 the drill derrick 33 may be tilted forwardly to lower the center of gravity of the catamaran 30 while in transport. A top deck structure 52 supports a plurality of pipe racks 53 amidships and also carries a pair of deck houses 54, one of which is positioned on each of hull means 31 and 32. Deck houses 54 in turn support angularly disposed fore and aft braces 55 and 56 as well as intermediate reinforcing braces 57 which carry a flat platform 58 extending across the two hulls in the space therebetween to form a platform for the landing of helicopters or a heliport. The deck houses 54 may be internally arranged in any desired manner, one illustrative form being disclosed in FIGURE 3 wherin a plurality of cabins are provided, one of which 60 may comprise an office, another 61, the state room for the tool pusher or chief driller, a third 62, the master's quarters, a fourth 63, the hospital, and the other two 64 and 65 comprising spares or other cabins as may be desired. Suitable heads and closet space 65' may be provided and located as desired, as may a ladder 66 leading 75

to the heliport platform or deck from the interior of the deck house 54 as well as an external ladder 67.

Pipe racks 53 extend transversely over the main decks 70 of both hull means as well as the intervening space, 5 and have intermediately positioned a catwalk 71 to provide access to any desired portion of the racks. Cranes 72 of conventional design and of any desired capacity, such for example, as 30 tons, are provided on opposite sides of the main deck 70 and include the usual booms 75 and operating units 76. Cranes 72 may be employed 10 for any desired purpose, such as raising or lowering the drill rig 33, or loading and unloading pipes from the piperacks 53. Ladders or external gangways 77 extend from the main decks upwardly to the drill platform 37. Each hull may carry one or more lifeboats 78 mounted 15 on the usual davits 79 adjacent and exteriorly of the heliport platform 58 on the outer side of the hull means. Such boats may comprise lifeboats, or alternatively, merely gigs or tenders, as desired.

In this form of the invention, supply loading cranes or derricks 79 are positioned adjacent the stern of each hull means and are rotatable for the loading of supplies as may be necessary.

The main deck level 80 below the pipe rack or supporting deck is provided with the usual rail 81 and doorways 82 leading into the interior of the main deck superstructure underlying the pipe rack deck 70 which deck contains the major operating equipment of the vessel. In one illustrative embodiment of the invention, stern 25 winches 82 are mounted in angularly disposed relation on the aft portion of the main deck level and carry anchoring cables 83 which extend at right angles to each other, one directly rearwardly and the other directly outwardly of the hull. These winches and their associated cables in combination with similar winches 84 mounted 30 on the deck immediately above and their associated cables 85, which extend respectively directly out and forwardly of the bow, serve to hold the catamaran in a fixed position for drilling operations.

The interior arrangements of the main decks of hull means 31 and 32 may be laid out in any desired manner, as, for example, the crew's quarters 87 may occupy the forward portion of each hull means, while immediately aft of the crew's quarters in hull means 31 may be a generator room 88 while hull means 32 in a similar location is provided with storage tanks 89 for dry mud as well as pumping equipment. The pumping equipment is indicated at 90. Hull means 31 may also have water purifying and supply equipment 91. Hull means 31 includes, in the illustrative embodiment shown, active mud pits 94, and an inspection well 95, as well as engines 96. Hull means 32 may include a mud mixing pump 97, driving engines 98, and oil reservoirs 99. After the engine room there may be provided additional quarters arranged 35 in any desired manner as indicated at 100.

The hold, as best shown in FIGURE 5, may contain additional crew quarters as indicated at 101 as well as reservoirs for drilling water as at 102 and storage bins for reserve mud at 103. Immediately rearwardly of the tanks 103, hull means 31 may be provided with a companion way 104 while hull means 32 may be provided with a conveyor 105. Additional machinery 106 may also be provided, if necessary, while the compartments to the rear in each hull means contain bilge and ballast pumps 107, fire pumps 108 and fuel oil transfer pumps 109. The aft portion of each hull means may be provided with a stores locker 110 and a paint locker 111. Adjacent the bow drinking water may be stored in tanks 112 while pressure sets may be stored in compartments 113.

It is to be understood that all these arrangements are optional and FIGURE 16, for example, shows a fragmentary rearrangement of the compartment containing a ladder 104 wherin a storage compartment 115 is provided and an additional conveyor 116 is positioned adjacent ladder 104. In FIGURE 17, a modification of a bow

compartment is shown wherein only three tanks 112 are provided and a ladder 117 takes the place of a fourth.

It will be readily understood that the arrangement of the deck plans hereinbefore set out are to a large extent a matter of choice, and those herein shown are merely for the purposes of expediency.

The main deck level forward of the crew's quarters may contain in one hull means the dining and recreation facilities 120, storage bins 121, and the galley 122. In the opposite hull means such space may be used merely for storage as indicated at 123.

FIGURES 13 and 14 disclose minor modifications of the rear portions of hull means 31 and 32 at the level of FIGURE 4. In this arrangement the winches are arranged in perpendicular relation to the lines which they serve, as indicated at 125 and 126 on both hull means. The lines 127 corresponding to the lines 83 are thus subjected to a direct pull from the winch rather than run around pulleys as in the previously disclosed modifications. In this modification, additional towing or mooring cables 128 may be secured about suitable bights 129 or cleats secured to the deck for towing or other purposes. Such an arrangement of the winches will obviously require a reorganization of the interior compartment 100 to the form indicated at 130. Such compartments may, obviously, be utilized for a wide variety of purposes. Similarly, FIGURE 15 discloses a generator assembly 131 adjacent the wall of the hull rather than centrally as in FIGURE 4.

The exterior of each hull means 31 and 32 is provided along its entire length, and below the first of a series of connecting trusses to be hereinafter described with a plurality of tanks 135, which are suitably partitioned, and which may contain, for example, tanks for the storage of fuel oil, as seen at 136, and drilling water as seen at 137 and wash water as shown at 138. Here again, the arrangement of the tanks is largely optional and, if desired, such tanks may be employed only for ballast.

Means are provided for connecting the two hull means 31 and 32 in relatively rigid relation, and may take various structural forms. For example, FIGURE 6 discloses a relatively rigid beam 140 at the level of the main deck and above the tops of tanks 135, which is rigidly secured to each of the hulls 31 and 32. A second truss 141 may extend between the hull means at the pipe rack deck level, while a third transverse beam 142 underlies the floor 58 of the heliport. Vertical beams 143 and 144 extend centrally between beams 140, 141, and 142, while diagonal reinforcing braces 144 are provided between beams 142 141 together with supplemental diagonal braces 145 extending between the center of beam 141 and main connecting beam 140. The entire beam assembly and connection is designated by the reference character 150, and any desired number of such assemblies may be provided. In the illustrative embodiment herein shown, there are four of the assemblies 150, as best shown in FIGURE 4, all of which may be substantially identical and connected by longitudinally extending diagonal reinforcing bars or girders 151. It is to be understood that various other beam support arrangements may be provided as desired.

A pair of additional beam assemblies 155 are provided amidships, as seen in FIGURES 2 and 7, and serve primarily to support the pipe racks 40, although an auxiliary connecting function is performed by a lower beam 156 connected between the hulls 31 and 32 in substantial alignment with the beams 140. A top supporting beam 157 is also provided extending directly beneath the pipe racks 40, while a vertical beam 158, diagonal beams 159, serve further to support the central portion of the pipe rack deck. While in the illustrative embodiment of the invention herein shown, there are only two of these supporting members 155, it is to be understood that additional supports may be provided, if desired.

FIGURE 7 also discloses a support 160 having a flat top beam 161, and suitable uprights 162 which serve as a sup-

port for the top of derrick 33 when the latter is pivoted forwardly in the manner previously described. FIGURES 6 and 7 also disclose the fan housings 165 on the pipe rack deck level 70.

The aft portions of the hull means beneath the drilling platform 37 are also connected by trusses or beams 166, from which diagonal beams 167 extend upwardly to transverse supporting beams 168 which underlie the drilling platform 37. Additional diagonally disposed truss beams 169 extend from the main deck level 80 to the ends 171 of beams 168. The above-described beam assemblies are generally designated by the reference character 175, and in the illustrative embodiment shown, three are provided immediately forward of the drilling well and connected by diagonally extending members 176 similar to the members 151 previously described.

Additional supports are provided for the rear of drilling platform 37 over the after well and between the sterns of the two hull means, and as shown in FIGURE 8, comprise beams 178 which underlie supporting members 179 for platform 137, and are in turn supported by diagonals 180 which extend from the pipe rack deck level 70 of each of hulls 31 and 32 upwardly. Deck houses 38' are also shown in FIGURE 8, and are provided with additional diagonal reinforcing members 180 exteriorly thereof for further support of the drill rig platform 37.

In this illustrative embodiment, the supporting structure is generally indicated at 181, and, as shown in FIGURE 2, four of these may be provided, or as many as may be necessary. It is to be understood that the particular construction of the connecting and supporting frameworks for the heliport, the drilling platform, and the pipe racks, may all be varied in accordance with the necessary stresses incident to the proper support of the components.

FIGURES 11 and 12 disclose a slightly modified form of construction wherein the rig supporting platform 185 is elongated as compared to the platform 37 and the drill rig 186, although substantially identical to the previously described mast or rig 33, is supported further aft, the support taking the form of pivots 187 secured to supporting members 188 mounted on the platform 185. The deck house 189 extends substantially beyond the stern of the hull means in contradistinction to the previously described deck house 38 carrying the usual drill rig controlling mechanism, and actually overhangs the stern, as does the rear-most portion of platform 185. Reinforcing and support members 190 correspond in function to the members 41 disclosed in the previous modification with the exception that they are comprised of reinforced girder members and are secured to the rig at two points 191 and 192. The lower ends of the members are pivotally mounted as on pivots 194 to upstanding supports 195 carried by the platform 185. In lowering the rig 186 which is also provided with the usual upper pulleys 196 corresponding to the previously described mechanism 40, it is necessary to disconnect the connections 191 and 192, whereupon the members 190 may be pivotally moved about their pivot points 194 and the mast 186 lowered by means of the crane 72 as in the previously described modification. In this form of the invention, additional supporting members 181 may be utilized as may be necessary. It may also here be noted that the cranes 72 are employed for the loading and unloading of pipe from the pipe racks, and further for the purpose of properly aligning the pipe beneath the derrick or drill rig for positioning in the well beneath the surface as may be necessary.

A modified form of construction is illustrated in FIGURES 18 to 21, inclusive, and is generally indicated at 200. In this embodiment there are provided a pair of substantially identical hull means 201 and 202, each of which is provided with internal compartmentation, which may take a form similar or identical to the compartmentation of the hulls of the previously discussed modification. The two hull means in this modification are connected by transversely extending girders or beams 204 and 205 rigidly affixed therebetween with the diagonally disposed beams

206 reinforcing the construction, toward the forward part of the hull means.

The hull means 201 and 202 may be provided on both sides with projecting water tight pontoon type sections 207. Such sections may be employed to enhance the buoyancy of the vessel, or alternatively, may comprise storage tanks as in the previously described modification.

The fore part of the ship is provided with an upper deck 208 upon which are mounted deck houses 209, which may contain officers' quarters or the like, and which are bridged by a flat surface 210, the roofs of deck houses 209 together with the surface 210 providing a heliport, generally indicated at 213, and substantially similar to the heliport of the previously described modification. Longitudinally extending beams 214 support the central section 210, as well as a lower central section 215, the eye beams 216 of which are supported by girders 217 supported by the diagonally disposed beams 206.

Fan houses 218 are provided at the rear of heliport 213 and the usual boats 219 supported by davits 220 are positioned on opposite sides of the heliport.

A pipe rack deck 221 extends substantially the full length of the ship and is provided with pipe supporting elements 222. Cranes 223 serve to load and unload as well as to position the pipes in the same manner as the previously described cranes 72. The rear of the vessel is provided with transverse hull connecting members 223 and 224, and the central portion between the hull means is covered by a platform 225, the entire space across the two hull means forming pipe supporting surfaces 226 provided with pipe rack stops 227.

The various compartments 230 between the pipe rack deck 221 and the main deck 231 are employed for the several purposes described in connection with the preceding modification, as are the similar compartments 232 in the hold beneath main deck 231.

Any suitable interior arrangement of components is satisfactory.

In this modification, supporting members 205 and 204 and 223 and 224 are omitted from the center portion of this space between the two hull means to provide a drilling well beneath a drill rig supporting platform 235 which is centrally positioned, and which supports a drill rig or derrick 236 of conventional design. A deck house 237 on platform 235 accommodates the drill rig controlling apparatus.

Platform 235 is supported on transverse girders 238 which in turn are supported by upright beams 239 and reinforcing diagonals 240, which latter are secured to vertical uprights 241 supported by main deck 231. The arrangement is thus such that a secure and stable platform for the drilling apparatus is provided, as well as a clear space through which the drill pipe may be extended.

As in the preceding modification, forward winches 242 are connected to anchoring lines 243, while stern lines 244 are operated in a similar manner from suitable winches 245 at the stern of each hull means. The anchoring arrangement is substantially identical to that discussed in the preceding modification.

Catwalks 246 extend substantially the full length of the pipe rack deck fore and aft of the drilling platform for the convenience of the crew, and suitable ladders 247 are provided at spaced intervals for access between the various decks levels.

In this modification the drill rig 236 is stationary, and while its central location may enhance the stability of this arrangement when in anchored position, the construction of FIGURES 18 to 21 is obviously more unwieldy in transport and in towing.

Referring now to FIGURES 22 to 29, a self-propelled, unitary construction, catamaran offshore drilling vessel is designated generally by the reference numeral 250 and will be seen to comprise a pair of spaced apart hull means 251 and 252 rigidly and unitarily secured to each other by a connecting portion 253 formed integral with the

hull means 251 and 252 and extending from approximately the main deck level down to the second deck level. Thus, this embodiment is constructed originally as a catamaran rather than taking the hull means of two former 5 drilling tenders as in the embodiments described hereinabove and assembling the same together in spaced apart relationship by means of connecting trusses or the like such a construction allows for increased structural sturdiness and more efficient utilization of the deck and storage carrier.

10 The vessel 250 is provided with fore and aft deck houses 254 and 255, respectively, the roof of the former providing a helicopter landing surface or heliport 256 and the roof of the latter providing a drilling floor or deck 15 257 supporting a drill rig 258 which may be pivotally mounted as described hereinabove to lower the center of gravity during transportation, and a draw works shed 259 including the draw works 260. The arrangement of the upper deck may vary, but a convenient plan is shown in FIGURE 24 wherein the upper level of the deck house 254 includes a rotary drilling table 260a, a pilot house 261, an office and control room 262 and a radio and chart room 263, while the lower level as seen in FIGURE 25 may contain the captain's quarters 264, other quarters 265, recreation rooms 266 and mess and galley rooms 267. 20 Handrails 268 and stairways 269 will be provided throughout the vessel as needed.

25 Rotatable supply loading cranes or derricks 270 are provided as are lifeboats and accompanying equipment 30 271 similar to previously described embodiments.

Piperacks 272 extend transversely over the main deck 273 to support pipes 274 for the drilling operation in a conventional manner. Also, a slope plate 275 and drag way 276 are provided between the piperacks 272. Conventional hatches are shown at 277, bulk material hatches at 278 and shell shaker and sand trap machinery at 279.

35 As seen in FIGURE 26, stern winches 280 are mounted on the aft portion of the second deck level and carry anchoring cables 281 extending at right angles to each other, one directly rearwardly and the other directly outwardly of each hull means 251 and 252. Similarly, bell winches 282 carry anchoring cables 283 directed forwardly and outwardly of the valve portion of each hull means 251 and 252. Personnel boat landings 284 are provided on each side of the vessel 250. The second deck arrangement may include quarters 285 separated by passageways 286 from spare or storage rooms 287, hospital areas 288, wash rooms and toilets 289, freeze and chill rooms 290, engine room 291, thaw room 292, laundry 293, change rooms 294, and dry stores 295. Large areas for sack materials storage may be provided at 296 and a halliburton unit at 297. Also, space for bulk cement bins and dry bulk mud bins is shown at 298 and hatches at 299.

40 55 The third deck may have sea water ballast areas 300 fore and aft, spaced for bow propeller machinery at 301, drill water storage at 302, wash water storage at 303, potable water storage at 304 and a distiller at 305. The main switch board may be provided at 306, an upper machinery room at 307, upper top rooms at 308, active and reserve mud areas at 309, bulk mud bins at 310, bulk cement bins at 311, repair shops and spares storage at 312, a carbon dioxide room at 313, and a gyro room at 314.

60 65 The tank top and inner bottom arrangement plan shown in FIGURE 28 may have fuel oil storage 315, main and auxiliary generator units 316 and 317, respectively, main mud pumps 318, a mixing pump 319, and the propeller motors 320 to drive the propellers 321. Rudders 322 are provided for steering the vessel 250.

70 75 It is to be understood that the arrangements shown for the unitary, self-propelled, embodiment of FIGURES 22 to 29 are merely exemplary and are set forth to illustrate the great working and storage area provided by such a construction. It will be readily seen that this unit is

particularly efficient and flexible in use providing a drilling rig which may be quickly moved from one location to another without a great loss of operative time and which is self contained requiring no additional equipment for propelling the vessel or for quartering the men and storing the machinery necessary to a drilling operation.

From the foregoing it will now be seen that there is herein provided an improved catamaran type offshore drill rig which accomplishes all the objects of this invention including many advantages of great practical utility and commercial importance.

As many embodiments may be made of this inventive concept, and as many modifications may be made in the embodiment hereinbefore shown and described, it is to be understood that all matter herein is to be interpreted merely as illustrative, and not in a limiting sense.

We claim:

1. An offshore drilling vessel comprising a pair of substantially identical hull means each having a bow portion, a stern portion, a beam dimension, a plurality of internal compartments to provide storage space, machinery space and living quarters, and an upper surface normally disposed in a substantially horizontal plane, means including parallel intermediate beams and a plurality of A-frames fore and aft of the intermediate beams all rigidly and structurally securing said hull means together in spaced catamaran relationship, a deck having an upper surface in substantially the same horizontal plane as said upper surface of said hull means and extending transversely across the space therebetween, a drilling platform including an energized rotary drilling table and drilling means operatively connected to said drilling table for conducting drilling from the platform at substantially the transverse center of gravity of said drilling vessel between said catamaran hulls, regardless of the depth of the navigable water, said drilling platform being structurally supported by rearward support braces immediately above said upper surfaces of each stern of said hull means and extending transversely across the space therebetween, and an oil drilling derrick including hoisting line means for raising and lowering a drill string intermediate the aft portions of said hulls and fixedly supported intermediate on said drilling platform operatively interconnected to said rotary drilling table and said drilling means.

2. A structure in accordance with claim 1 wherein said

hull means are spaced apart a distance less than said beam dimension of one of said hull means.

3. A structure in accordance with claim 1 wherein said drilling platform extends between said hull means adjacent said stern portions thereof.

4. A structure in accordance with claim 3 wherein said oil drilling derrick is pivotally mounted on said drilling platform, and means are provided for raising and lowering said oil drilling derrick between a vertical operating position and a horizontal transporting position.

5. A structure in accordance with claim 1 wherein pipe racks are provided extending transversely over a major portion of said upper surfaces of each of said hull means and over said deck.

6. A structure in accordance with claim 1 wherein said hull means are integrally formed with said means securing the same in spaced catamaran relationship.

7. A structure in accordance with claim 1, further including, in combination, means integral with said vessel for propelling the same.

8. A structure in accordance with claim 1 further comprising, in combination, a plurality of bow and stern anchor means at each hull means, and operating means for said anchor means.

9. A structure in accordance with claim 1 further comprising, in combination, a raised deck adjacent said bow portions of each of said hull means extending transversely across the space therebetween and serving as a heliport.
